UNITED STATES PATENT OFFICE.

JOHN M. RUSBY, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

PROCESS OF CONTROLLING COMBUSTION.

1,106,319.

Specification of Letters Patent.

Patented Aug. 4, 1914.

Application filed February 13, 1911. Serial No. 608,312.

To all whom it may concern:

Be it known that I, JOHN M. RUSBY, a citizen of the United States, residing at the city of Philadelphia, in the county of Philadelphia and State of Pennsylvania, have invented a certain new and useful Process of Controlling Combustion, of which the following is a specification.

The present invention relates to improvements in the combustion of fluid, meaning liquid or gaseous, combustibles in a chamber, and its principal object is to control the temperature effect of the combustion in such a way that intense local heating effects may be avoided and the heating effect properly distributed and, generally stated, it consists in burning the fluid combustible in a chamber and mixing the burning mass by commingling the fluid combustible and air with the hot and newly formed products of combustion before the escape of these products of combustion from the chamber, thereby preventing formation of intense local heating flames and effecting a proper distribution of heat.

The process may be practised by means of a variety of apparatus but for the sake of description one type of apparatus has been chosen from among the many types for the purpose of illustration in the accompanying drawings in which—

Figure 1, is a side view with parts broken away of a coal gas bench arranged for the practice of the process of the invention, and Fig. 2, is a front view of the bench shown in Fig. 1, with parts broken away.

Gas generated in the producer 1, is an example of a fluid combustible, in connection with the combustion of which the process is applicable, but there are many other fluid combustibles such as oil vapors and natural and artificial gases in connection with the combustion of which the process is useful.

2, is an example of a chamber in which fluid combustible may be burned in accordance with the process of the invention but of course other forms of chamber can be used. Producer gas from the chamber 1, reaches the chamber 2, by way of the passage 3. Products of combustion escape from the chamber 2, through the flues 4, and reach the stack. Air in passing through the flues 5, is heated and is discharged in part at 6, under

the grate 7, and in part at 8, for the purpose of burning the producer gas in the chamber 2, in the present instance to heat the retorts 9.

The foregoing is a description of the ordinary process and apparatus of a gas retort bench which has been chosen from among many processes and apparatus in the art to which the process is applicable and in connection with which it might have been explained. The flame formed by the combustion of the fuel gas with secondary air entering at 8, produces a concentrated combustion and intense local heating effect. This concentrated region of combustion or intense local heating effect is undesirable not only in the case of a coal gas bench but also in the case of a variety of instances that occur in the arts. With a coal gas bench the result is to heat the retorts unevenly and to overheat that portion of the retorts which is in close proximity with the intense heating flame. In accordance with this invention the burning fluid combustible, as it is consumed in a chamber, and which is of course at a very high temperature, is stirred, circulated, agitated or distributed so that the formation of intense local heating flame is prevented and a proper distribution of combustion and resulting heat is attained.

There are various expedients for effecting the described stirring operation. Among these jets have been chosen for the sake of explanation and they are illustrated at 12, as extending through the walls of the chamber 2, and discharging generally crosswise of or at an inclination

see 12^a to the direction of travel of the combustible fluid. These jets 12, may be supplied with steam or other appropriate substance through connections as 10, for example with a portion of the air necessary for combustion or with a portion of the burning mixture itself, or with waste products of combustion, each suitably impelled through the jet appliance. Openings are shown at 11, so that the lower jets may operate effectively in stirring the burning fluid combustible which is also stirred by the other jets. Since the function of the jets or other stirring means is to stir the burning fluid combustible as it is consumed the location and arrangement of the stirring means can be changed and varied while still accomplishing the result of effecting a distribution

of combustion and consequently of heat throughout the chamber such as may be required or desired.

While I have described the process of my invention in application to a coal gas bench fitted with steam jets it must be borne in mind that the invention is not limited to the chamber of a coal gas bench or to steam jets as a means for stirring, but

10 Having thus described my invention what I claim as new and desire to secure by Letters Patent is:

1. The process of controlling the temperature effect of combustion of a fluid combustible, which consists in burning the fluid combustible in a chamber and mixing the burning mass by commingling the fluid combustible and air with the hot and newly

formed products of combustion before the escape of those products of combustion from the chamber.

2. The process of controlling the temperature effect of combustion of a fluid combustible which consists in progressively burning the fluid combustible in a chamber and mixing the burning mass by commingling the fluid combustible and air with the hot and newly formed products of combustion before the escape of those products of combustion from the chamber.

In testimony whereof I have hereunto signed my name.

JOHN M. BUSBY.
